Primary Examiner — Wan Laymon*Assistant Examiner* — Mark Booker*(74) Attorney, Agent, or Firm* — Wells St. John P.S.(57) **CLAIM**

I claim the ornamental design for a hinge, as shown and described.

DESCRIPTION

FIG. 1 is a perspective view of a design for a hinge;

FIG. 2 is a front view thereof;

FIG. 3 is a rear view thereof;

FIG. 4 is a side view thereof, an opposite side view is a mirror image of the FIG. 4 side view;

FIG. 5 is a top plan view thereof; and,

FIG. 6 is a bottom plan view thereof.

The broken lines shown in FIG. 3 represent portions of the hinge that form no part of the claimed design.
